UNITED STATES PATENT OFFICE.

GEORGE STOEBER, OF O'BRIEN COUNTY, IOWA.

DESIGN FOR A SPRING FOR BINDER-DECKS.

SPECIFICATION forming part of Design No. 34,794, dated July 16, 1901.

Application filed May 20, 1901. Serial No. 61,203. Term of patent 14 years.

To all whom it may concern:

Be it known that I, GEORGE STOEBER, a citizen of the United States, residing in the county of O'Brien, State of Iowa, have invented and produced a certain new and original Design for a Spring for Binder-Decks, of which the following is a specification, reference being had therein to the accompanying drawings.

10 Figure 1 is a perspective of my design for a spring for binder-decks, and Fig. 2 is a plan view thereof.

As shown in the drawings, the leading or material feature of my design consists of a body portion A of the spring curved in opposite directions or upon a compound curve, as shown at A, while the free end thereof is slightly upturned, as shown at A³, and beyond the curved body a circular coil A' is provided which lies in a vertical plane, and at the free end the elongated loop A² is formed

by bending the free end of the spring upon itself in a plane above the main portion thereof and at a right angle to the plane of the coil of said spring. The compound curve 25 in the body portion extends downward adjacent to the coil portion and upward adjacent to the free end, where it finally curves downward into substantially the line of the downwardly-curved portion. 30

Having described my invention, what I claim, and desire to secure by Letters Patent, is—

The design for a spring for binder-decks, as herein shown and described. 35

In testimony whereof I affix my signature in presence of two witnesses.

GEORGE STOEBER.

Witnesses:

J. H. BUSSANMAS,
PETER J. MEINHART.
